LOCKET CONSTRUCTION

Edwin S. Donle, Edgewood, R. I., assignor to
Coro, Inc., a corporation of Rhode Island

Application June 28, 1947, Serial No. 757,856

1 Claim. (Cl. 63—19)

1

The present invention relates to the jewelry art, and has particular reference to a locket construction having a plurality of ornament compartments.

The principal object of the invention is to provide a very thin locket suitable for use as a pendant and having a number of compartments adapted to receive ornaments or photographs, the compartments nesting together in very compact relation.

An additional object of the invention is to provide a locket having nesting compartments with novel manually releasable catch and latch parts, the latch part being formed as a pendant ring.

A further object is to provide the folding compartments with spring members which operate to open the locket and its compartments when the latch is manually moved to open position.

Another object of the invention is to provide a locket of the described type which has a minimum number of readily manufactured and assembled parts.

With the above and other objects and advantageous features in view, the invention consists of a novel arrangement of parts more fully disclosed in the detailed description following, in conjunction with the accompanying drawings, and more specifically defined in the claim appended thereto.

In the drawings:

Fig. 1 is a front view of a pendant type locket embodying the novel features of the invention, the locket being closed;

Fig. 2 is a perspective view of the locket of Fig. 1, the locket being open;

Fig. 3 is an enlarged central vertical section through Fig. 1;

Fig. 4 is a fragmentary detail view showing the relative spacing of the parts;

Fig. 5 is an enlarged sectional detail, parts being broken away, showing the preferred pressure spring mounting; and

Fig. 6 is an enlarged detail of the catch and latch parts.

It has been found desirable to provide a locket of very thin construction which is suitable for use as a pendant, the locket containing a number of compartments which nest together when the locket is folded and closed. It is preferred to position the compartments so that they open into separated relation under the influence of pressure springs, and to form the pendant ring as a latch member which cooperates with a catch element on the locket cover to releasably lock the compartments within the locket body. To this end, I form the locket body as a hingedly

2

connected base and cover, and hingedly secure additional compartments to the base and the cover in spaced relation whereby they nest within the locket body when folded; and I provide pressure springs which continually urge the compartments to unfolded position, whereby the pressure springs completely unfold the locket when the catch and latch arrangement is released. I further provide a catch element on the cover and a latch element on the base which is pivotally mounted and includes an eccentrically positioned latch for providing a strong closing and holding action when it is manually turned to engage the catch element.

15 Referring to the drawings, which illustrate a preferred constructional embodiment of the invention, the locket 10 includes a base 11 and a cover 12 which are hingedly connected together by a hinge 13. A compartment 14 is joined to the base by a hinge 15, and a compartment 16 is joined to the cover by a hinge 17, the hinges being angularly displaced as shown in Figs. 4 and 2 to permit folding the compartment 14 into the base and the compartment 16 into the cover.

20 15 The compartments, base and cover are preferably slightly recessed or cupped, as illustrated in Fig. 2, to receive suitable ornaments such as photographs, which may be snapped in or retained in place by snap or spring bezels 18 of standard type. The compartment hinges 15 and 17 each include an end roll 19 on the base and cover and a center roll 20 on the compartments, and a hinge pin 21, the central roll 20 being of larger diameter than the hinge pin to accommodate the central portion 22 of a pressure spring 23, one end 24 of the pressure spring extending between the contiguous end roll and the central roll to engage the back of the compartment, and the other end 25 being wedged in place to lock beneath the other end roll, whereby a continuous opening pressure is exerted on the compartments.

25 The preferred catch and latch arrangement is illustrated in Figs. 3 and 6, and includes a catch element 26 projecting upwardly from the cover and slightly curved to provide a transverse catch rib 27, and a manually movable latch member 28 which has a loop 29 through which a chain may be passed, two spaced lower arms 30 which are at substantially right angles to the loop portion and are hinged to a roll 31 which is an integral part of the base, a transverse bar 32 closing the lower end of the loop 29, and a latch element 33 which is preferably slightly angular with respect to the loop and has a depending part 34 adapted

to extend over the catch element 26 when the locket is closed, and to swing over the catch element 26 and releasably lock the locket parts together when the loop is swung forwardly. The angular relation of the latch element permits the depending latch part 34 to slide over and seat to the loop pivot beneath the transverse catch rib 27, as shown in Fig. 3, while the loop remains in vertical relation to the locket body.

It is thus clear that the locket includes a base and a cover, and compartments which have concealed pressure springs urging the compartments, and therefore the base and cover as well, to open position, the catch and latch elements firmly locking the folded parts in closed position, and the latch element having a pendant loop.

Although I have described a specific constructional embodiment of the invention, it is obvious that changes in the size, shape and proportions of the parts, and in the pressure spring and the catch and latch parts, may be made to meet the requirements for different locket designs, without departing from the spirit and the scope of the invention as defined in the appended claim.

5

10

15

20

25

I claim:

In a locket construction, a base, a cover hinged thereto, a hinge roll on said base, a catch member on said cover adapted to be positioned adjacent the hinge roll when the cover is in closed relation to the base, said catch member having a transverse catch rib, and a manually movable latch member having an upper loop, two spaced lower arms at substantially right angles to the loop and having their ends inturned and seated in the hinge roll, a transverse bar closing the lower end of the loop, and a latch element on the transverse bar depending to swing over the catch member and into the catch member rib when the latch member is turned to engage the catch member.
